UNITED STATES PATENT OFFICE.

ALLAN H. JONES, OF BELLEVILLE, NEW JERSEY, ASSIGNOR TO ROLLER BEARING COMPANY OF AMERICA, OF NEWARK, NEW JERSEY, A CORPORATION OF NEW JERSEY.

HELIX-WINDING MACHINE.

Application filed May 19, 1925. Serial No. 31,264.

To all whom it may concern:

Be it known that I, ALLAN H. JONES, a citizen of the United States of America, residing at Belleville, in the county of Essex 5 and State of New Jersey, have invented certain new and useful Improvements in Helix-Winding Machines, of which the following is a full, clear, and exact description.

In making rollers or the helical or so-called "spiral" type for roller bearings a 10 method commonly employed involves winding a flat strip of metal to helical form on a mandrel of the proper diameter, after which the helix thus produced is cut up into 15 lengths suitable for the individual rollers. The present invention relates to the winding or coiling of the strip, and its chief object is to provide a machine for that purpose by which a helix of practically unlimited 20 length can be wound, especially when the helix is of small diameter, say a quarter of an inch or less, a size which heretofore has been difficult to wind. Another object is 25 to provide a machine which is largely automatic in character, so that it may be successfully operated by a person with limited skill or experience. A further object is to provide a machine of simple construction which can be made much shorter than the 30 helix turned out, thereby economizing floor space.

To these and other ends the invention comprises the novel features and combinations hereinafter described.

In carrying out the invention in the preferred manner the metal strip is guided and wound on a rotatable but axially stationary mandrel by a non-rotating but axially movable winding head which is advanced automatically as the winding proceeds. The winding is effected by rotating the helix, for 35 which purpose a revolving chuck is provided, in which the helix is securely held. The chuck is rotated by a hollow shaft. As the 40 helix is formed and the winding head advanced thereby, the latter, at the forward end of its path, actuates a suitable device, as for example an electric switch, to stop the winding operation. The attendant then 45 reverses the winding chuck for a revolution or two, so as to loosen the helix on the mandrel, then stops the machine, releases the 50 chuck entirely, and starts the motor again, whereupon a traveling carriage at the rear 55 of the chuck pulls the helix rearwardly

through the hollow chuck-shaft and off the mandrel. This rearward movement of the helix serves also to retract the winding head, and provision is made whereby the arrival of the winding head at the rear end of its path will stop the machine. The attendant now closes the winding chuck down upon the helix and starts the machine again in the forward direction. The winding is thus resumed and the operations described above 60 are repeated. As the winding head advances the carriage which retracts the helix through the hollow chuck-shaft is brought up to a position near the chuck, where it can engage the helix for the next retraction thereof. 70

The embodiment outlined above is illustrated in the accompanying drawings, in which—

Fig. 1 is a side view of the machine.

Fig. 2 is a detail side view on a larger 75 scale.

Fig. 3 is a detail plan view, on about the same scale as Fig. 2.

Figs. 4, 5 and 6 are detail cross sections on lines 4—4, 5—5 and 6—6 of Fig. 2. 80

Figs. 7 and 8 are detail front views of the controlling switch, showing the same in different operative positions. In these figures the switch housing or box is in cross section. 85

Fig. 9 is a cross section on line 9—9 of Fig. 7.

Fig. 10 is a sectional plan view on line 10—10 of Fig. 8.

The winding chuck 12, mounted on or integral with the tubular shaft 13, is of any suitable construction, as for example such as commonly employed in drill presses, having jaws 14 which can be adjusted to grip or release the helix (shown at 15) by turning the square stud 16, using for the purpose a suitable key, not shown. The mandrel 17, on which the helix is wound, extends forwardly from the chuck and at its front end rests loosely in an upwardly open recess 18 in a Y-shaped support 19. The mandrel has a certain amount of flexibility, which makes it unnecessary to have the forward end of the mandrel accurately centered. The supporting recess is therefore 100 made large enough to permit the mandrel to flex slightly, as may be necessary to accommodate itself to any slight inaccuracy of centering of itself or the winding head, or both. In front of the recess 18 the 105 110

mandrel has a head 20, which serves to prevent more than negligible amount of longitudinal movement of the mandrel.

The winding head 21 is mounted to move 5 axially on parallel rails 22, and is provided with an axial opening 23, Fig. 3, through which the mandrel extends. In 10 diameter this opening is slightly larger than the diameter of the mandrel plus twice the thickness of the metal strip, indicated at 24, which is to be wound, so that as the helix is rotated by the chuck 12 the strip will be wound to helical form of corresponding 15 diameter, producing a helix of which the maximum outer diameter is determined by the size of the die opening 23 and of which the minimum inner diameter is determined by the size of the mandrel, as will be readily understood. Extending through 20 the side of the head, to the die opening 23, is a feed aperture 25 through which the strip is drawn as the winding proceeds, this feed opening being inclined, to the mandrel and to the axis of the die opening, according 25 to the pitch desired for the helix. The opening 23 is also preferably but slightly larger, in cross section, than the strip itself, so that the latter will be fed accurately in place. From the foregoing it will be seen 30 that as the helix is formed the winding head is advanced (from left to right in Fig. 3) just as a non-rotatable nut is advanced by the rotation of an axially stationary screw.

35 The winding chuck 12 is rotated, in either direction at will, by a motor 26, Fig. 1, through the agency of reducing gearing 27, chain 28, and sprockets 29, 30. The starting and stopping, and the direction of rotation 40 of the motor, are controlled by a switch 31, which may be of the "snap" type shown in Figs. 7, 8, 9 and 10. The supply leads 32, 33, are connected to the pivots of the switch arms 34, 35, while the motor terminals 36, 37 are connected to contacts 36^a, 37^a. Contact 38 is electrically connected to contact 36^a. The switch arms are connected for simultaneous actuation by a link 39, which is itself actuated, as described below, by a rod 40 extending forwardly (see Figs. 1 and 2) and provided with adjustable actuating fingers 41, 42, in the path of lugs 43, 44, on the axially movable winding head 21. One of the switch arms has a handle 45, for manual operation of both.

60 Assuming the switch arms to be in the position shown in Fig. 7, the motor circuit is closed and the motor drives the chuck in the clockwise direction as viewed from the right of Fig. 2. As the head 21 approaches the forward end of its path the lug 44 meets finger 42 and advances the switch rod 40, thereby rocking the switch arms 34, 35, Fig. 7, counterclockwise. During this movement 65 the switch actuating spring 46 is

cammed upwardly by the tooth 47 on the end of arm 34 until the point of the tooth passes the V-shaped bend of the spring, whereupon the latter by its cam action on the other side of the tooth snaps the arm 70 34, and with it arm 35, to the "off" position indicated in dotted lines. This breaks the motor circuit and the motor therefore stops. The attendant then backs off the chuck jaws 75 14 enough to relieve the pressure of the helix upon the mandrel, after which he swings the switch arms to the position shown in Fig. 8, in which, as will be seen, the polarity of the current impressed on the motor terminals is reversed, thereby starting the motor in the opposite direction and rotating the helix counterclockwise as seen from the right of Fig. 2. This has an 80 unwinding effect on the helix, and two or three revolutions are usually enough to loosen it from the mandrel, whereupon the attendant rocks the switch back to the off position. He then releases the chuck jaws entirely from the helix and rocks the switch again to the "reverse" position, Fig. 8. By 85 the means now to be described the reverse rotation of the chuck 12, after it is freed from the helix, causes the latter to be drawn rearwardly through the chuck and off of the mandrel 17.

90 Back of the chuck 12 and on the shaft 13 is a clutch member 50, Fig. 2, cooperating with a clutch member 51 splined inside of the hollow hub 52 of the bevel gear 53 and urged into frictional contact with the first clutch member by a spring 54. The bevel gear 53 drives a bevel pinion 54, Figs. 2 and 3, on transverse stub shaft 55 having a sprocket 56 for the chain 58 passing over a similar sprocket 60, at the rear or left end of the machine. The motion of sprocket 56 is transmitted by gears 54^a, 54^b, transverse shaft 54^c, and gears 54^d 54^e, to a similar sprocket 57 on the other side, having a chain 59 parallel to chain 58 and passing over a sprocket 61 at the rear, coaxial with sprocket 60; these sprockets 60 and 61 being mounted on stub shafts, as indicated in Fig. 3, so as to leave clear the space between the sprockets. Between the chains and secured to the upper reaches thereof is a retracting carriage 62, suspended from and traveling on a rail 63 and provided with an opening 64 for the helix 15. The carriage is also equipped with one or more cam-pawl 110 65, arranged to pass idly over the helix as the carriage moves forward (to the right in Fig. 2) but to grip the helix firmly as the carriage moves rearwardly. Assuming that the retracting carriage 62 is at the forward end of its path, against the stop 66, Fig. 2, it will be seen that when the attendant reverses clutch 12 to effect a partial unwinding 115 of the helix to loosen it from the mandrel 17 the helix, being gripped by the 120 125 130

clutch and also by the cam-pawls 65, does not permit the carriage 62 to be carried back and hence the clutch members 50 and 51 slip on each other. When, however, the 5 clutch is released from the helix, after the latter is loosened from the mandrel, the resistance of the helix to backward movement is not sufficient to cause the clutch to slip when the chuck shaft 13 is again started in 10 the reverse direction, and accordingly clutch member 51 is rotated, thereby driving sprockets 56, 57 in the counterclockwise direction (Fig. 2) and shifting the retracting carriage 62 leftwardly. As the helix is retracted by the leftward movement of the carriage the winding head is retracted at the same time by the metal strip 24 extending through the guide aperture 25, Fig. 3. As 15 soon as the driving motor is stopped by the finger 43 actuating the controlling switch the attendant re-engages the chuck 12 upon the helix and starts the motor in the forward direction, thereby resuming the helix-forming operation. At the same time the 20 carriage-actuating sprockets 56, 57 are rotated in the clockwise direction, thereby advancing the carriage toward the chuck. Upon reaching the stop 66, Fig. 2, the carriage is arrested, after which the clutch 25 50—51 slips, as already described, until the motor is stopped.

It will be observed that the forward travel of the winding head 21 per revolution of the clutch 12 depends entirely upon the 35 pitch of the helix, and that the forward and rearward travel of the retracting carriage 62 per clutch-revolution depends solely upon the ratio of the gears 53—54 and sprockets 56—57; whereas the retracting speed of the 40 winding head is always exactly the same as that of the carriage. Hence by suitable design of the parts involved the retraction of the helix can be made rapid, so that only a small portion of the complete cycle is consumed by the retracting operation.

As the helix issues from the rear of the machine it may be allowed to fall on the floor or it may be coiled into a shallow receptacle, not shown, of suitable size. The 50 latter disposition is permitted by the flexibility of the helix, which allows it to rotate on its own axis even though flexed, in the manner of a flexible shaft. In fact helices wound by the method described make excellent flexible shafts. In winding helices for the latter purpose the operator will keep 55 in mind the fact that, in general, the narrower the strip from which the helix is produced, the more sharply can the helix be bent without injury.

For making helices of different outside or inside diameters, or both, winding heads and mandrels of proper sizes can be provided, the necessary substitution being easily 60 and quickly made.

It is to be understood that the invention is not limited to the construction herein specifically illustrated and described but can be embodied in other forms without departure from its spirit.

70

I claim—

1. In a helix-winding machine, in combination, a chuck to engage and rotate the helix and adapted to permit rearward longitudinal movement of the helix through it, 75 an axially movable non-rotatable winding head in front of the chuck and substantially coaxial therewith, said head having a lateral guide aperture to receive and guide a metal strip and having axial die opening to receive the strip and coil the same to helical form, and a mandrel extending through the die opening and coaxial therewith.

2. In a helix-winding machine, in combination, a chuck to engage and rotate the helix and adapted to permit rearward longitudinal movement of the helix through it, 80 an axially movable non-rotatable winding head in front of the chuck and substantially coaxial therewith, said head having a lateral guide aperture to receive and guide a metal strip and having axial die opening to receive the strip and coil the same to helical form, 85 a flexible mandrel extending through the die opening and coaxial therewith, and means for loosely supporting the forward end of the mandrel to permit the latter to accommodate itself to inaccurate centering of the winding head and chuck.

3. In a helix-winding machine, in combination, a chuck to engage and rotate the helix and adapted to permit rearward longitudinal movement of the helix through it, 90 means for rotating the chuck in either direction at will, an axially movable non-rotatable winding head in front of the chuck and substantially coaxial therewith, said head having a lateral guide aperture to receive and guide a metal strip and having axial die opening to receive the strip and coil the 95 helical form, the coiling of the strip serving to advance the head in unison therewith, and means in rear of the chuck to retract the helix through the chuck and simultaneously retract said winding head.

4. In a helix-winding machine, in combination, a chuck to engage and rotate the helix and adapted to permit rearward longitudinal movement of the helix through it, 100 means for rotating the chuck in either direction, an axially movable non-rotatable winding head in front of the chuck and substantially coaxial therewith, said head having a lateral guide aperture to receive and guide a metal strip and having an axial die opening to receive the strip and coil the same to helical form, the coiling of the strip by rotation of the chuck in one direction serving 105 to advance the head in unison therewith, a carriage in rear of the chuck to engage and 110

115

120

125

130

retract the helix through the chuck and simultaneously retract said winding head when the chuck is rotated in the reverse direction, and actuating means for said carriage adapted also to advance the same toward the chuck when the latter is rotated in the forward direction.

5. In a helix-winding machine, in combination, a chuck to engage and rotate the 10 helix and adapted to permit rearward longitudinal movement of the helix through it, means for rotating the chuck in either direction at will, an axially movable non-rotatable winding head in front of the 15 chuck and substantially coaxial therewith, said head having a lateral guide aperture to receive and guide a metal strip and having an axial die opening to receive the strip and coil the same to helical form, the coiling of 20 the strip serving to advance the head in unison therewith, means in rear of the chuck to retract the helix through the chuck and simultaneously retract said winding head, and controlling means actuated by the winding 25 head to stop the chuck rotating means when the said winding head reaches a predetermined point in its travel in either direction.

6. In a helix-winding machine, in combination, a chuck to engage and rotate the 30 helix and adapted to permit rearward longitudinal movement of the helix through it, means for rotating the chuck, an axially movable non-rotatable winding head in front 35 of the chuck and substantially coaxial therewith, said head having a lateral guide aperture to receive and guide a metal strip and having an axial die opening to receive the strip and coil the same to helical form, the 40 coiling of the strip by rotation of the chuck in one direction serving to advance the head in unison therewith, means in rear of the chuck to retract the helix through the chuck and simultaneously retract said winding 45 head when the chuck is rotated in the reverse direction, and manual controlling means for the chuck-rotating means to determine the direction of rotation of the chuck.

50 7. In a helix-winding machine, in combination, a chuck to engage and rotate the helix and adapted to permit rearward longitudinal movement of the helix through it, means for rotating the chuck in either direction, an axially movable non-rotatable winding head in front of the chuck and substantially coaxial therewith, said head having a lateral guide aperture to receive and guide a metal strip and having an axial die opening 55 to receive the strip and coil the same to helical form, the coiling of the strip by rotation of the chuck in one direction serving to advance the head in unison therewith, means 60

in rear of the chuck to retract the helix through the chuck and simultaneously retract said winding head when the chuck is rotated in the reverse direction, manual controlling means to determine the direction of rotation of the chuck, and automatic means to stop the chuck-rotating means when the winding head reaches a predetermined point in its travel in either direction.

8. In a helix-winding machine, in combination, a chuck to engage and rotate the 75 helix and adapted to permit rearward longitudinal movement of the helix through it, means for rotating the chuck, an axially movable non-rotatable winding head in front of the chuck and substantially coaxial therewith, said head having a lateral guide aperture to receive and guide a metal strip and having an axial die opening to receive the strip and coil the same to helical form, the coiling of the strip by rotation of the chuck serving to advance the head in unison therewith, and automatic means to stop the chuck-rotating means when the winding head reaches a predetermined point in its travel.

9. In a helix-winding machine, in combination, a chuck to engage and rotate the 80 helix and adapted to permit rearward longitudinal movement of the helix through it, an axially movable non-rotatable winding head in front of the chuck and substantially coaxial therewith, said head having a lateral guide aperture to receive and guide a metal strip and having an axial die-opening to receive the strip and coil the same to helical form, the coiling of the strip by rotation of the chuck serving to advance the head in unison therewith, and a rotatable axially stationary mandrel extending forwardly through said die-opening and coaxial therewith.

10. In a helix-winding machine, in combination, a chuck to engage and rotate the helix and adapted to permit rearward longitudinal movement of the helix through it, an axially movable non-rotatable winding head in front of the chuck and substantially coaxial therewith, said head having a lateral guide aperture to receive and guide a metal strip and having an axial die-opening to receive the strip and coil the same to helical form, the coiling of the strip by rotation of the chuck serving to advance the head in unison therewith, a flexible mandrel extending forwardly through the die-opening in said head and coaxial therewith, and means for loosely supporting the forward end of the mandrel and preventing longitudinal movement thereof.

In testimony whereof I hereto affix my signature.

ALLAN H. JONES.
